UNITED STATES PATENT OFFICE.

HENRY FUNK, OF PANA, ILLINOIS.

DESIGN FOR A GRAIN-DRILL POINT OR SHOVEL.

SPECIFICATION forming part of Design No. 32,341, dated March 13, 1900.

Application filed February 12, 1900. Serial No. 5,026. Term of patent 14 years.

To all whom it may concern:

Be it known that I, HENRY FUNK, a citizen of the United States, residing at Pana, in the county of Christian and State of Illinois, have 5 invented and produced a new and original Design for a Grain-Drill Point or Shovel; and I do hereby declare the following to be a full, clear, and exact description of the invention, such as will enable others skilled in the art to 10 which it appertains to make and use the same.

This invention relates to a novel and unique design for a wheat-drill point or shovel.

The vital feature of the design is a double-winged point or shovel having its wings oppositely receding on divergent lines, with their 15 upper outer ends forwardly curved and having the point of the shovel upwardly curved, the medial portion being transversely curved at the point, angular at the base, and gradually conforming to the terminal outlines at 20 intermediate points.

The design will be best understood from the drawings hereto attached in connection with the appended description.

25 Referring to the drawings, Figure 1 is a top plan view of the drill-point. Fig. 2 is a rear view. Fig. 3 is a section on the line X X of Fig. 1 looking toward the rear. Fig. 4 is a side elevation.

Corresponding and like parts are referred to in the following description and indicated in all the views of the drawings by the same reference characters.

The shovel is of triangular form and consists of side wings 1, lying in divergent planes 35 and having their upper corner portions 2 forwardly curved. The point 3 is curved upwardly and is rounded or convex in transverse section. The medial portion (represented by the line 3 4) is straight, and at 4 40 the wings form a sharp angle, whereas at 3 the wings curve horizontally, and between the terminal points the said medial portion varies in cross-section and gradually conforms to the extreme outlines. From 4 to the upper corners of the wings the top edges flare 45 slightly and curve forwardly.

Having thus described the invention, what is claimed as new is—

The design for a drill point or shovel, substantially as herein shown and described.

In testimony whereof I affix my signature in presence of two witnesses.

HENRY FUNK. [L. S.]
